CLAIM

The ornamental design for a fragrance bottle cap, as shown and described.

DESCRIPTION

FIG. 1 is a front perspective view of a first embodiment of a fragrance bottle cap;

FIG. 2 is a front view of the fragrance bottle cap of FIG. 1; FIG. 3 is a rear side view of the fragrance bottle cap of FIG. 1;

FIG. 4 is right side view of the fragrance bottle cap of FIG. 1;

FIG. 5 is a left side view of the fragrance bottle cap of FIG. 1;

FIG. 6 is a top view of the fragrance bottle cap of FIG. 1; FIG. 7 is a bottom view of the fragrance bottle cap of FIG. 1;

FIG. 8 is a front perspective view of a second embodiment of a fragrance bottle cap;

FIG. 9 is a front view of the fragrance bottle cap of FIG. 8; FIG. 10 is a rear side view of the fragrance bottle cap of FIG. 8;

FIG. 11 is right side view of the fragrance bottle cap of FIG. 8;

FIG. 12 is a left side view of the fragrance bottle cap of FIG. 8;

FIG. 13 is a top view of the fragrance bottle cap of FIG. 8; FIG. 14 is a bottom view of the fragrance bottle cap of FIG. 8;

FIG. 15 is a front perspective view of a third embodiment of a fragrance bottle cap;

FIG. 16 is a front view of the fragrance bottle cap of FIG. 15;

(Continued)

FIG. 17 is a rear side view of the fragrance bottle cap of FIG. 15;
 FIG. 18 is right side view of the fragrance bottle cap of FIG. 15;
 FIG. 19 is a left side view of the fragrance bottle cap of FIG. 15;
 FIG. 20 is a top view of the fragrance bottle cap of FIG. 15;
 FIG. 21 is a bottom view of the fragrance bottle cap of FIG. 15;
 FIG. 22 is a front perspective view of a fourth embodiment of a fragrance bottle cap;
 FIG. 23 is a front view of the fragrance bottle cap of FIG. 22;
 FIG. 24 is a rear side view of the fragrance bottle cap of FIG. 22;
 FIG. 25 is right side view of the fragrance bottle cap of FIG. 22;
 FIG. 26 is a left side view of the fragrance bottle cap of FIG. 22;
 FIG. 27 is a top view of the fragrance bottle cap of FIG. 22; and,
 FIG. 28 is a bottom view of the fragrance bottle cap of FIG. 22.

The broken lines in FIGS. 1-21 depict environment that forms no part of the claimed design. The broken lines in FIGS. 22-28 depict portions of the fragrance bottle cap that form no part of the claimed design.

1 Claim, 24 Drawing Sheets
